UNITED STATES PATENT OFFICE.

MORRIS WEINTRAUB, OF NEW YORK, N. Y.

DESIGN FOR A DRINK-MIXING RECEPTACLE.

Application filed March 17, 1923. Serial No. 5,496. Term of patent 3½ years.

To all whom it may concern:

Be it known that I, MORRIS WEINTRAUB, a citizen of the United States, and a resident of the city of New York, borough of Manhattan, in the county and State of New York, have invented a new, original, and ornamental Design for Drink-Mixing Receptacle, of which the following is a specification, reference being had to the accompanying drawings, forming a part thereof.

I claim:

The ornamental design for a drink mixing receptacle as shown.

MORRIS WEINTRAUB.
